Primary Examiner — George D Kirschbaum*(74) Attorney, Agent, or Firm* — Richard John Bartz(57) **CLAIM**

The ornamental design of a puzzle tray, as shown and described.

DESCRIPTION

FIG. 1 is a front elevational view of the puzzle tray of my new design;

FIG. 2 is top plan view thereof;

FIG. 3 is a rear elevational view thereof;

FIG. 4 is a bottom plan view thereof;

FIG. 5 is a side elevational view of the right side thereof; and, FIG. 6 is a side elevational view of the left side thereof.

The broken lines showing applicant's trademark PUZZLE PAL and design in FIG. 1 is included for the purpose of illustration and forms no part of the claimed design.
